UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

LOOPER MECHANISM FOR SEWING-MACHINES.

1,257,940.

Specification of Letters Patent. Patented Feb. 26, 1918.

Application filed March 10, 1916. Serial No. 83,297.

To all whom it may concern:

Be it known that I, DUDLEY S. SEYMOUR, a citizen of the United States, residing at Oak Park, in the county of Cook, State of Illinois, have invented certain new and useful Improvements in Looper Mechanism for Sewing-Machines, of which the following is a description, reference being had to the accompanying drawing, and to the figures 10 of reference marked thereon.

My invention relates to new and useful improvements in sewing machines, and more particularly to the looper mechanism for a sewing machine wherein the material being 15 stitched is supported by a work-supporting arm extending at an angle to the plane of the overhanging arm of the machine.

An object of the invention is to provide a machine of the above character with a horizontal arm supported by the standard, which arm carries the work-supporting arm proper and in which horizontal arm is mounted the main shaft of the machine, the looper mechanism being operated from this 25 main shaft.

A further object of the invention is to provide a machine of the above character with a looper mechanism having a looper-supporting shaft, and devices operated from 30 the main shaft for oscillating said looper-supporting shaft and for moving the same endwise.

These and other objects will in part be obvious, and will in part be hereinafter more 35 fully disclosed.

In the drawings, which show by way of illustration one embodiment of the invention,—

Figure 1 is a view partly in side elevation 40 and partly in section, showing a machine and embodying my improvements;

Fig. 2 is a view partly in front elevation and partly in section of the same;

Fig. 3 is an enlarged detail view length- 45 wise of the work-supporting arm, showing the manner of supporting and operating the looper from the main shaft in the horizontal arm; and

Fig. 4 is a horizontal sectional view 50 through the upper portion of the work-supporting arm.

The machine in which my invention has been embodied, consists of a supporting standard 1 mounted on a suitable base 2.

Projecting laterally from the standard is 55 an overhanging arm 3. Mounted in the overhanging arm is a shaft 4. At the forward end of the overhanging arm is a needle bar 5, which is reciprocated from said shaft 4. The shaft 4 is oscillated by mechanism which will be hereinafter described and on the forward end of the shaft there is an arm 6 connected by a link 7 to a suitable lug on a collar fixed to the needle bar.

As the shaft 4 is oscillated, the needle bar 65 will be reciprocated. Said needle bar as herein shown is provided with two pairs of needles 8, 8 and 9, 9.

The standard 1 is also provided with a forwardly projecting arm 10. Extending 70 laterally from this forwardly projecting arm is a horizontal arm 11. The horizontal arm is substantially parallel with the overhanging arm 3. At the free end of the horizontal arm there is a depending post 12, 75 which carries the work-supporting arm proper 13. The work-supporting arm 13 extends in a direction at an angle to a vertical plane containing the longitudinal axis of the overhanging arm, that is, the plane 80 of the overhanging arm, and the free end of this work-supporting arm is located underneath the free end of the overhanging arm.

Mounted in the horizontal arm 11 is a 85 main shaft 14. This main shaft extends through the forwardly projecting arm 10 and is provided with a belt wheel 15. The forwardly projecting arm is provided with suitable bearings 16 and 17 in which the 90 main shaft is mounted, and between these bearings said main shaft is formed with a crank 18. A pitman 19 coöoperating with the crank is also connected to an arm 20 fixed to the shaft 4, and this pitman oscillates the shaft 4.

Coöperating with the needles 8, 8 is a looper 21 while a looper 22 coöperates with the pair of needles 9, 9. These loopers 21 and 22 are mounted on the looper-carrier 100 23, fixed to the forward end of a looper-supporting shaft 24. The pairs of needles are arranged one in rear of the other, so the separate loopers may coöperate with the respective pairs of needles. The looper shaft 105 24 is mounted in a bearing 25 near the forward end of the work-supporting arm 13, and a bearing 26 at the front side of the

depending post 12. The shaft is mounted in these bearings so that it oscillates and moves endwise in the bearings.

The main shaft 14 is provided with an eccentric with which an eccentric strap 27 coöperates. This eccentric strap at the lower end is connected to a ball stud 28 on the outer end of an arm 29 fixed to a cross shaft 30. The cross shaft 30 is provided with a second arm 31. The looper-supporting shaft 24 carries a collar 32, which is fixed thereto, and said collar has an outwardly extending arm 33. A link 34 connects the arms 31 and 33. There is a ball stud mounted on each arm 31 and 33, so that the looper support and the arm 33 may be moved in a direction longitudinally of the looper shaft without interfering with the driving connections between the cross shaft and the looper shaft.

From the above it will be apparent that as the main shaft 14 rotates, the cross shaft will be oscillated, and through the arms 31 and 33 and the connecting link the looper-supporting shaft will be oscillated, so as to move the loopers into and out of the needle loops.

Mounted on the looper-supporting shaft is a sleeve 34^a. Said sleeve is held from endwise movement on the shaft by fixed collars 35 and 36. This permits the looper-supporting shaft to oscillate freely relative to the sleeve, but all endwise movements of the sleeve will be imparted to the looper-supporting shaft. The sleeve 34^a is provided with a rib 37, which extends between suitable guiding lugs 38 carried by the work-supporting arm 13. This prevents the sleeve from oscillating.

40 The sleeve is moved endwise for imparting endwise movement to the looper-supporting shaft by a cross shaft 39. Said cross shaft is mounted in suitable bearings in the work-supporting arm 13. The cross shaft has a depending arm 40, which is provided with a slot 41. A link 42 is pivotally connected at one end to the sleeve 34^a, while the other end of this link is pivotally connected to a stud 43, which is adjustably mounted in the slot 41.

45 The cross shaft 39 carries a second arm 44, on which is mounted a ball stud 45.

A second eccentric is mounted on the main shaft 14 and an eccentric strap 46 co-
operates therewith. This eccentric strap 46
50 at its lower end is connected to the ball stud 45. As the main shaft rotates, the eccentric will impart endwise movement to the eccentric strap, and this in turn will oscillate the cross shaft 39, which will move the sleeve 34 back and forth and thus impart endwise movement to the looper-supporting shaft. This endwise movement gives to the loopers their needle-avoiding movements.

46 The material is fed along the work-sup-
porting arm by a feed dog 47, carried by a

main feed bar 48. This main feed bar is raised and lowered by an eccentric 49 on the looper-supporting shaft 24. The main feed bar is moved back and forth by a link 50, connected to an arm 51 mounted on the cross shaft 39. The feed bar adjacent its rear end is fulcrumed on a cross pin 51^a, which permits the feed bar to move endwise, and which causes the feed dog to be raised by the eccentric on the looper-supporting shaft. 75 The feeding mechanism also includes a differentially operated feed dog which receives its endwise movements from the main feed bar and which is raised and lowered with the main feed bar. This feeding mechanism 80 forms no part of the present invention and further description thereof is not thought necessary.

From the above description, it will be noted that the link 42 which moves the 85 loopers laterally has a slotted connection with the operating arm 40 therefor, and by adjusting the stud 43 in the slot 41 in this arm the lateral throw given to the loopers may be varied.

90 It is obvious that minor changes in the details of construction and the arrangement of parts may be made without departing from the spirit of the invention as set forth in the appended claims.

95 Having thus described my invention, what I claim as new and desire to secure by Letters Patent, is:—

1. A sewing machine including in combination, a standard, an overhanging arm, a 100 needle bar mounted in said overhanging arm, a needle carried thereby, a horizontal arm parallel with the overhanging arm and carried by said standard, a main shaft located in said horizontal arm, devices actuated by said main shaft for reciprocating the needle bar, a work-supporting arm carried by said horizontal arm, a looper located in said work-supporting arm and coöperating with said needle, and devices operated by 110 said main shaft for imparting back and forth movements to said looper and lateral movements to said looper.

2. A sewing machine including in combination, a standard, an overhanging arm, a 115 needle bar mounted in said overhanging arm, a needle carried thereby, a horizontal arm parallel with the overhanging arm and carried by said standard, a main shaft located in said horizontal arm, devices actuated by said main shaft for reciprocating the needle bar, a work-supporting arm carried by said horizontal arm, a looper located in said work-supporting arm and co-
operating with said needle, a looper-sup-
porting shaft located in said work support-
ing arm, and devices actuated by said main shaft for oscillating said looper-supporting shaft and for moving the same endwise. 125

3. A sewing machine including in combi- 130

- nation, a standard, an overhanging arm, a needle bar mounted in said overhanging arm, a needle carried thereby, a horizontal arm carried by said standard, a main shaft located in said horizontal arm, devices actuated by said main shaft for reciprocating the needle bar, a work-supporting arm carried by said horizontal arm, a looper located in said work-supporting arm and operating with said needle, a shaft extending lengthwise of said work-supporting arm and carrying said looper, an eccentric on the main shaft, and devices actuated thereby for oscillating said looper-supporting shaft, a second eccentric on said main shaft, and devices operated thereby for moving said looper-supporting shaft back and forth.
4. A sewing machine including in combination, a standard, an overhanging arm, a needle bar mounted in said overhanging arm, a needle carried thereby, a horizontal arm carried by said standard, a main shaft located in said horizontal arm, devices actuated by said main shaft for reciprocating the needle bar, a work-supporting arm carried by said horizontal arm, a looper located in said work-supporting arm and operating with said needle, a looper-supporting shaft extending lengthwise of said work-supporting arm, a sleeve freely mounted on said looper-supporting shaft and held from endwise movement thereon, an eccentric on the main shaft, devices operated thereby for moving said sleeve endwise for giving an endwise movement to the looper-supporting shaft, a second eccentric on said main shaft, and devices operated thereby for oscillating said looper-supporting shaft.
5. A sewing machine including in combination, a standard, an overhanging arm, a needle bar mounted in said overhanging arm, a needle carried thereby, a horizontal arm carried by said standard, a main shaft located in said horizontal arm, devices actuated by said main shaft for reciprocating the needle bar, a work-supporting arm carried by said horizontal arm, a looper located in said work-supporting arm and operating with said needle, a looper-supporting shaft extending lengthwise of said work-supporting arm, a sleeve freely mounted on said looper-supporting shaft and held from endwise movement thereon, an eccentric on the main shaft, devices operated thereby for moving said sleeve endwise for giving an endwise movement to the looper-supporting shaft, a second eccentric on said main shaft, a cross shaft oscillated by said second eccentric, and means operated by said cross shaft for oscillating said looper-supporting shaft.
6. A sewing machine including in combination, a standard, a horizontal arm carried by said standard, a depending post supported by said arm, a work-supporting arm projecting laterally from the lower end of said depending post, a main shaft mounted in said horizontal arm, a looper mounted in the outer end of said work-supporting arm, a looper-supporting shaft carrying said looper and extending longitudinally of said work-supporting arm, a cross shaft mounted in said post, means for oscillating said cross shaft from said main shaft, means for oscillating said looper-supporting shaft from said cross shaft, a second cross shaft, means for oscillating said second cross shaft from said main shaft, and means oscillated by said second cross shaft for moving the looper-supporting shaft endwise.
7. A sewing machine including in combination, a standard, a horizontal arm carried by said standard, a depending post supported by said arm, a work supporting arm projecting laterally from the lower end of said depending post, a main shaft mounted in said horizontal arm, a looper mounted in the outer end of said work-supporting arm, a looper-supporting shaft extending lengthwise of the work-supporting arm and carrying said looper, an arm fixed to said looper-supporting shaft at the rear end thereof, a cross shaft mounted in said post, an arm projecting from said cross shaft, a link connecting said arms, means for oscillating said cross shaft from said main shaft, and means for moving said looper-supporting shaft endwise.
8. A sewing machine including in combination, a standard, a horizontal arm carried by said standard, a depending post supported by said arm, a work-supporting arm projecting laterally from the lower end of said depending post, a main shaft mounted in said horizontal arm, a looper mounted in the outer end of said work-supporting arm, a looper-supporting shaft extending lengthwise of the work-supporting arm and carrying said looper, an arm fixed to said looper-supporting shaft at the rear end thereof, a cross shaft mounted in said post, an arm projecting from said cross shaft, a link connecting said arms, means for oscillating said cross shaft from said main shaft, a second cross shaft, a sleeve freely mounted on the looper-supporting shaft and held from endwise movement thereon, adjustable means operated by said second cross shaft for moving the sleeve endwise, and means operated by the main shaft for oscillating said second cross shaft.
9. A sewing machine including in combination, a standard, an overhanging arm, a needle bar mounted in said overhanging arm, needles carried by said needle bar, a horizontal arm parallel with the overhanging arm and carried by said standard, a main shaft located in said horizontal arm,

a work supporting arm extending in a direction at an angle to the horizontal arm, a looper located in said work supporting arm and coöperating with the needles, a looper supporting shaft located in said work supporting arm and carrying said looper, means for operating said looper supporting shaft from the main shaft in the horizontal arm, and means operated from said main shaft in said horizontal arm for mov-

ing said looper laterally, said means including devices whereby the lateral throw of the looper may be varied.

In testimony whereof I affix my signature in the presence of two witnesses.
